United States Patent Office

Des. 190,630

Patented June 20, 1961

190,630

PORTABLE SERVICE STATION

Vernon D. Jarvis, 367 W. Decatur St., Decatur, Ill.

Filed June 24, 1960, Ser. No. 61,106

Term of patent 14 years

(Cl. D13—1)

Des. 190,630

PAGE 2

FIGURE 1 is a front perspective view showing my new design for a portable service station.

FIGURE 2 is a rear elevational view.

FIGURE 3 is an end elevational view.

FIGURE 4 is an elevational view of the opposite end.

FIGURE 5 is a reduced top plan view.

The dominant features of my design reside in the portions shown in full lines.

I claim:

The ornamental design for a portable service station, as shown and described.
